UNITED STATES PATENT OFFICE.

EDWARD HEYMANN AND FRANK W. HEYMANN, OF JAMAICA PLAIN, MASSACHUSETTS, ASSIGNEES TO EMMA HEYMANN, OF SAME PLACE.

DRIVING MECHANISM.

SPECIFICATION forming part of Letters Patent No. 678,364, dated July 16, 1901.

Application filed October 19, 1900. Serial No. 83,636. (No model.)

To all whom it may concern:

Be it known that we, EDWARD HEYMANN and FRANK W. HEYMANN, citizens of the United States, residing in Jamaica Plain, county of Suffolk, and State of Massachusetts, have invented an Improvement in Driving Mechanism, of which the following description, in connection with the accompanying drawings, is a specification, like characters on the drawings representing like parts.

This invention relates to a novel driving mechanism, especially designed and adapted, among other uses, to be employed on automobiles to effect travel of the same in either direction with a minimum vibration of the vehicle. For this purpose we employ a plurality of friction-clutches of a construction as will be described, which are mounted on a shaft to be driven and which are actuated by a plurality of eccentrics on a driving-shaft. The eccentrics are and may be adjustably mounted on the driving-shaft, so as to vary their throw, and thus change the speed of rotation of the driven shaft, as will be described. A plurality of eccentrics are employed, which are set so as to avoid dead-centers in the rotation of the driven shaft, and the parts of the driving mechanism are and may be inclosed in a dust and water proof casing, as will be described. These and other features of this invention will be pointed out in the claims at the end of this specification.

Figure 1 is a partial plan and sectional view of a driving mechanism embodying this invention; Fig. 2, a detail in section on the line 2-2, Fig. 1; Fig. 3, a side elevation of the mechanism shown in Fig. 1, and Fig. 4 a diagram representing the relative positions of the eccentric disks.

Referring to Figs. 1 and 2, *a* represents a shaft to be driven, and for this purpose it has keyed or otherwise fastened on it a plurality of friction-clutches, herein shown as three in number and lettered *b c d*. Each of the clutches referred to comprises a disk *e*, (see Fig. 2,) fast on the shaft *a*, as by the key *f*, and provided on its periphery with a plurality of recesses *g*, herein shown as six in number and each containing a roller *h*, which is confined in said recess by side plates *i* and a

movable band or ring *j*, which encircles the disk *e* between said side plates and which fits closely thereon, but is yet free to be moved about said disk. The disks *e* are arranged on the shaft *a*, with corresponding recesses *g* in alinement, and through each set of recesses, comprising those in alinement, is extended an actuating device for the rollers *h*, which device is shown as a bar *k*, having a series of cam-shaped notches *l*, which are adapted to coöperate with a series of studs or pins *m*, located at the narrower or smaller end of the recess and attached to the disks *e*. The bars *k* are adapted to be moved transversely of the disks by end plates or disks *n o*, mounted on the shaft *a* to move longitudinally thereon and connected together by the tie-rods *p*. One of the end plates, as *o*, is provided with a hub *q*, adapted to be moved longitudinally of the shaft *a* by an elbow-lever *r*, to which is connected an actuating-rod *s*, which in practice is extended to within reach of the operator. The actuating rod or bar *k* for the friction-rollers *h* when moved in one direction, so that one edge of said bar engages the studs or pins *m*, as represented in Fig. 1, moves the friction-rollers with which it co-operates backward in the recesses *g*, which are made deeper at their rear end, so that the friction-rollers may be removed from contact with the movable or clutching band or ring *j*, and when the bar *k* is moved so that its cam-notches engage the studs or pins *m* the friction-rollers are moved forward into engaging or wedging position with the band *j* by springs *t* or other suitable yielding devices.

The movable or clutching band *j* is designed to have an oscillating or rotary reciprocating movement, and in order to effect movement of the clutch-disks *e*, and thereby of the driven shaft *a*, in either direction the recesses *g* are oppositely arranged in pairs, and the cam or actuating bars *k* are oppositely arranged, so that when the cam-notches of one of said cam-bars are in engagement with their coöoperating pins the clutching-bands will be effective on their movement in one direction—as, for instance, on the forward movement—and will be non-effective on the return movement, whereas when the positions of the cam-

bars are reversed the said bands become active or effective on their return movement and are inactive on their forward movement.

The reciprocation of the clutching-bands 5 may be effected, as herein shown, by means of eccentricities mounted on the driving-shaft 10 and connected to the clutching-bands by eccentric- rods 12. In order to regulate the stroke of the eccentric- rods 12, and thereby 10 regulate the speed of rotation of the driven shaft α , the eccentricities are adjustably mounted on the shaft 10, and the latter is made hollow to receive the devices by which the eccentricities are moved laterally or radially of the shaft 15 10 to vary the throw of the eccentricities.

Inasmuch as the three eccentricities connected to the three clutch-bands are the same, a detailed description of one will suffice for all.

Referring to Figs. 1 and 2, 15 represents a 20 disk provided with an oblong slot 16, extended to one side of the center of the disk and which fits upon a squared collar 17 on the hollow shaft, thus connecting the disk to the shaft, so as to rotate therewith. The disk 15 25 is encircled by a strap or band 18 between side plates or washers 19, which are also slotted, as at 20, to correspond to the slot 16, and the said band or strap preferably moves on antifriction - rollers 21, interposed between 30 said strap and the disk 15. The eccentric-rod 12 is attached to the strap or band 18. The hollow shaft 10 and its collar 17 are provided with longitudinal slots of substantially 35 the width of the eccentric disks, through which extend keys or wedges 23 24, having their rear edges straight and fitted into key ways or slots 25 26, formed in the end walls of the slot 16 and provided with beveled or inclined front edges which extend into inclined slots or ways 30 31, made in a rod or 40 section of a rod 32, which fits into the hollow shaft 10 and is capable of being moved longitudinally therein. The slots or ways 30 31 in the rod 32 are oppositely inclined and are 45 separated by a web or wall 33, extended longitudinally of the said rod, as clearly shown in Fig. 1.

From the above description and by reference to Figs. 1 and 2 it will be seen that if 50 the rod 32 is moved in the hollow shaft in the direction indicated by arrow 40, Fig. 1, the inclined web 33 will force the wedge 24 out from the hollow shaft, and thus move the disk 15 from the concentric position represented 55 by full lines, Figs. 1 and 2, into a position eccentric to the hollow shaft, as represented by dotted lines, Figs. 1 and 2, and the extent of eccentricity given to the disks is dependent upon the speed it is desired to impart to 60 the driven shaft α , for by varying the throw of the eccentricities the speed of the driven shaft may be varied so as to propel the vehicle at any desired rate of speed within limits. The rod 32 may and preferably will be made in 65 sections to facilitate cutting or milling of the inclined slots or ways 30 31, after which the

said sections are pinned or otherwise connected together and to an end section having a socket 41 in its outer end to receive a headed rod 42, which is retained in the socket 41 by a threaded plug or nut 43, the head of said rod having raceways for the reception of anti-friction-balls 44 45. The rod 42 is connected to an actuating-lever 46.

The eccentric disks are set with their slots 75 16 one hundred and twenty degrees apart, and the sections of the rod 32 are correspondingly set, so that their wedge ways or slots 30 31 are one hundred and twenty degrees apart, thus obtaining a substantially constant 80 torque on the driven shaft and avoiding vibration in the vehicle.

When the speed-changing rod 32 is moved in the direction indicated by the arrow 40, Fig. 1, the disks 15 are thrown into their eccentric positions, and being set at one hundred and twenty degrees apart they assume the positions indicated in the diagram Fig. 4. The hollow shaft 10 may be rotated, as herein shown, by a gasoline or other engine 50, 90 erected upon a casing 51, which supports the engine-shaft 52, provided with the fly-wheel 53 and connected to the hollow shaft 10 by gears 54 55 56, which are located in an auxiliary chamber 57, formed by a flange 58 on 95 the side plate 59 of the main casing and by a cover or plate 60.

The clutch mechanisms and the eccentric disks may be confined in a chamber 60, formed in the main casing and provided with a removable cover 61. The inclosing casing is provided with lugs 62, which rest upon the shaft 63, which may be the rear axle of the vehicle, and the front end of the casing may be flexibly supported by springs 64 65, located above and below a projection or lug 66 on said casing. The axle 63 may be driven from the shaft α by gears 67 68.

By means of the speed-changing mechanism herein shown the engine may be run continuously and, if desired, at full speed at all times, for when the disks 15 are concentric with the hollow shaft 10 motion is not imparted to the driven shaft; but, if desired, the full power of the engine may be gradually applied to the shaft α by gradually moving the disks 15 from their concentric to their full eccentric position, which is very desirable.

We claim—

1. In a driving mechanism, the combination with a driven shaft, a plurality of clutches mounted thereon, a hollow driving-shaft, a plurality of eccentric disks mounted on the said driving-shaft and provided with slots extended to one side of the center of said disks, means for connecting said disks with the clutches on the driven shaft, a rod movable in said hollow driving-shaft and provided with inclined keyways coöperating with each 125 of said disks, and wedges for each of said disks extended through the hollow shaft into

the said keyways and having their outer ends in engagement with the end walls of the slots in said disks, substantially as described.

2. In a driving mechanism, the combination with a hollow driving-shaft, a disk mounted thereon to rotate therewith and provided with a slot extended to one side of the center of said disk, a rod in said hollow shaft provided with inclined keyways or slots, and wedges extended through the hollow shaft into said keyways or slots, and having their outer ends in engagement with said disk, of a driven shaft, and means to connect said disk with said driven shaft, substantially as described.

3. In a driving mechanism, the combination with a driven shaft, a plurality of disks fast thereon and provided with peripheral recesses, rollers in said recesses, movable rings or bands encircling said disks and coöperating with said rollers, cam bars or rods extended through the recesses in the said disks and coöperating with said rollers, and means to move said bars or rods, of a driving-shaft having a plurality of eccentric disks connected to the movable rings on the driven shaft and set on the driving-shaft so as to produce a substantially constant torque on the driven shaft, and means to move said eccentric disks radially on the driving-shaft while it is in motion, substantially as described.

4. In a driving mechanism, the combination with a driven shaft, a disk thereon hav-

ing a plurality of peripheral recesses, rollers in said recesses, a movable band or ring encircling said disk and coöperating with said rollers, axially-movable cam bars or rods extended through said recesses and oppositely arranged, and means to move said bars or rods in the direction of the axis of said shaft to disengage the rollers from the said band or ring, substantially as described.

5. In a driving mechanism, the combination with a driven shaft, a plurality of disks fast thereon and provided with oppositely arranged peripheral recesses, rollers in said recesses, movable rings or bands encircling said disks and coöperating with said rollers, cam bars or rods extended through the recesses in the said disks and oppositely arranged, and means to move said bars or rods, of a driving-shaft having a plurality of eccentric disks set at substantially one hundred and twenty degrees apart and connected to the movable rings on the driven shaft, and means to move said eccentric disks radially on the driving-shaft while it is in motion, substantially as described.

In testimony whereof we have signed our names to this specification in the presence of two subscribing witnesses.
